UNITED STATES PATENT OFFICE.

RAYMOND D. SMITH, OF ARLINGTON, MASSACHUSETTS, ASSIGNOR TO TREMONT PRODUCTS COMPANY, OF BOSTON, MASSACHUSETTS.

DESIGN FOR A HUMIDIFIER.

53,403.

Specification for Design.

Patented June 3, 1919.

Application filed October 11, 1918. Serial No. 257,802. Term of patent 14 years.

To all whom it may concern:

Be it known that I, RAYMOND D. SMITH, a citizen of the United States, residing at Arlington, in the county of Suffolk and Commonwealth of Massachusetts, have invented a new, original, and ornamental Design for Humidifiers, of which the following is a specification, reference being had to the accompanying drawing, forming part thereof.

Figure 1 is a view of the humidifier in perspective showing my new design;—Fig. 2 being a plan view, Fig. 3 a front view, and Fig. 4 a side elevation looking at the right of Fig. 3.

I claim—

The ornamental design for a humidifier as shown.

RAYMOND D. SMITH.
